UNITED STATES PATENT OFFICE.

FRED WALLACE THURSTON, OF SAN FRANCISCO, CALIFORNIA, ASSIGNOR, BY MESNE ASSIGNMENTS, TO THURSTON MOTOR FUEL GASIFIER COMPANY OF CALIFORNIA, A CORPORATION OF CALIFORNIA.

HOMOGENIZER.

1,255,827.

Specification of Letters Patent.

Patented Feb. 5, 1918.

Application filed January 10, 1916. Serial No. 71,343.

To all whom it may concern:

Be it known that I, FRED W. THURSTON, a citizen of the United States, and a resident of San Francisco, in the county of San Francisco and State of California, have invented certain new and useful Improvements in Homogenizers, of which the following is a specification.

This invention relates to improvements in homogenizers designed to be interposed between the carburetor and an engine to homogenize the fuel or mixture delivered to the latter.

It is one of the objects of this invention to provide a device of this character wherein the fuel is spread against an outer heating surface by means of an inner heating shell, thereby subjecting the attenuated flow of fuel to the action of heat inwardly 20 and outwardly with respect thereto.

A further object of the invention is to provide a screen breaker between the inner and outer heating surfaces and to dispose the screen breaker in the path of the flowing fuel in such a manner as to force all of the latter to pass through the screen breaker. In accordance with my invention, the screen breaker is disposed in such close proximity to the heating surfaces as to be heated to 30 substantially the same temperature as said surfaces, thereby causing the screen breaker to not only function as a mechanical breaker, but also as a heater. A further novel feature consists in disposing the screen breaker in such relation to the heating surfaces, that the fuel will be deflected against one of said surfaces, initially, before it passes through the screen and engages the remaining surface. The primary purpose is to present a 40 plurality of heating surfaces to the spread flowing fuel for consecutive engagement by the latter in such a manner as to discharge the material in the form of a homogenized explosive mixture of a uniform character.

My invention includes, as one of its novel features, the improved type of screen breaker, as an article of manufacture, and my invention also includes the novel type of screen breaker and the structure whereby the breaker may be sprung into or out of position in the homogenizer.

Other features of novelty will be more

fully described in connection with the accompanying drawing and will be more fully pointed out in and by the appended claims. 55

In the drawing:

Figure 1 is a horizontal sectional view of my improved homogenizer taken on line 1—1 of Fig. 2.

Fig. 2, is a vertical sectional view thereof. 60

Fig. 3, is an enlarged sectional view on line 3—3 of Fig. 1.

Fig. 4, is a view in elevation of my improved screen breaker shown detached from the homogenizer. 65

Like characters of reference designate similar parts throughout the different figures of the drawing.

As illustrated, 1 designates an outer shell, preferably cylindrical, and having inlet and outlet passages 2 and 3 for passage of the exhaust gases of the engine or other heating medium into and through said shell. Said shell 1 is open ended and I provide the latter with a bottom 2' which is suitably 70 shouldered or recessed at 3' to fit about the edge of the lower open end of said shell. The bottom 2' is provided with an extension 4 forming a tubular fuel inlet and the extension 4 is provided with a flange 5 whereby 75 the bottom may be attached to a pipe connection, not shown, leading from a carburetor. The fuel inlet 4 is flared at 6 so as to permit the incoming fuel to spread in an attenuated annular stream, as will presently 80 appear. A top 7 is suitably recessed at 8 to fit about the edge of the upper open end of said shell 1, and said top is provided with a fuel outlet opening 9 which is preferably 85 about equal in size to the inlet opening 4. I 85 have shown a coupling 10 fitted on the top 90 7 and provided with a flange 11 which may be bolted to the top 7, bolt holes being shown in Fig. 2. The coupling 10 leads to the intake manifold of the engine, not shown. 95

A central shell is designated at 12 and the same is provided with external threads adjacent its upper and lower ends, which threads are arranged for engagement by internally threaded shoulders formed on the top 7 at 13, and on the bottom 2', at 14. The central shell 12 is slightly larger in diameter than the inlet 4 or the outlet 10 and it will be noted that when the top and bottom por-

2

tions are turned into tight threaded engagement with the central shell 12, said top and bottom portions will be in tight fitting engagement against the upper and lower edges 5 of the open ended shell 1. By means of this novel construction, it is not necessary to employ additional fastening means to secure the top and bottom portions to the outer shell 1. When the inlet and outlet portions 10 2 and 3, of the outer shell 1, are secured to their supply and exhaust connections, the outer shell will be held against turning movement.

An inner shell 15 is disposed within the 15 central shell 12 in sufficient spaced relation with respect to the interior thereof as to provide an intermediate fuel passage space between said central and inner shells. Said inner shell is open-ended and I preferably 20 provide thin flash heating top and bottom disks 16 and 17 which may be anchored in position by swaging over said heads or disks, marginal portions of the inner shell, thereby providing a closed inner fuel heating chamber. It will be noted by reference to Fig. 2, 25 that the inner chamber is disposed in the path of flow of the fuel entering said central shell 12 so that the heated bottom 17 will spread the fuel outwardly directly against 30 the interior of the central shell 12. Thus the lower flash heating disk or head 17 not only functions as a mechanical spreading means or deflector, but also as a heater.

In my improved novel construction, as 35 shown, the inner shell 15 is supported within and by the central shell 12 and for this purpose I have shown tubular connections 18 and 19 formed integral with said shells, which connections not only function 40 to support the inner shell from the central shell but also to establish communication between the inner shell 15 and the outer shell 1. This arrangement provides for short circuit flow of a portion of the exhaust gases 45 directly into and through the inner heating chamber from the outer shell 1, but it will be noted that the tubular connections 18 and 19 are very considerably reduced in cross-section, with respect to the inlet and outlet 50 portions 2 and 3, thereby providing for a relatively limited amount of flow through the inner chamber. It will now be clear that the same heating medium flowing through a outer chamber 20, formed by the outer 55 shell 1 and the central shell 12, to heat the exterior of the central shell 12, also forms the supply for heating the inner shell 15. A further feature of importance resides in the fact that the central shell 12 is completely jacketed against heat radiation. In order to facilitate an active flow through the inner heating chamber I preferably disposed the tubular connections 18 and 19 in alignment with inlet and outlet portions 2 and 3. 65 By reason of my improved construction

I am enabled to build a homogenizer of greatly reduced height with respect to any construction hereto known to me and because of the limited space between the carburetor and the fork of the intake manifold, 70 this becomes a feature of great importance. It is because of the fact that heat is applied internally and externally of the flowing fuel that I am able to obtain sufficiently quick heating action and at the same time reduce 75 the height to a minimum.

I will next describe my improved screen breaker and the manner in which it functions in co-action with the inner and outer heating surfaces between which the fuel to 80 be homogenized, passes.

As illustrated in Fig. 4, 21 designates a truncated conical screen of extremely fine mesh which is open at both ends. On the lower smaller margin I provide a contracting 85 annular spring 22 which is adapted to be sprung into an external annular groove 23, formed on the shell 15. On the upper margin of said screen 21 I provide an expandable spring 28 which is adapted to be 90 sprung into an internal annular groove 24, formed on shell 12. Screen 21 is provided with openings 25, the edges of which are adapted to fit about the tubular connections 18 and 19, and this construction alone would 95 support the screen in position. However, I desire to also utilize the springs 22 and 23 so as to support the screen in an angular position with respect to the direction of flow and cause all of the fuel to pass through the 100 screen by reason of the fact that its upper and lower margins are secured to the inner and central shells. In order to facilitate insertion of the screen I preferably split the same as indicated at 26, the split portion extending from the opening 25 up to and through the upper margin. This construction provides for ready removal of the screen for renewal or other purposes, as well as for initial assembling of the parts. 105

The fuel entering the central shell 12 strikes the flash heating bottom 17 and is heated and broken up to some extent by such contact. Suction acts to draw the fuel about said shell but in reality the shell active 110 deflects the fuel against the interior of the central shell 12, which is highly heated. This contact further serves to break up the fuel prior to its passage through the heating breaker screen 21, through which all of the fuel is forced to pass. The inner heating chamber extends upwardly into the interior of said screen so that the periphery of the inner chamber will heat inner portions of the spread flow which tend to cling to or flow 115 about the inner chamber. Furthermore, the periphery of the inner chamber extends sufficiently upwardly to present a heating surface to the fuel which has glanced off from the shell 12 and which passes toward the 120 125 130

inner heating chamber. The disposition of the outlet opening 9, and its reduced diameter, causes the flow to contract about the inner heating chamber and it will be noted 5 that a portion of the volume will pass over and come in contact with the upper flash heating head 16. From the foregoing, it is believed that the direction of flow through the homogenizer will be clear and that it 10 will also be apparent that when the fuel emerges from the outlet 9, it will be in the form of a completely homogenized fuel of a dry and highly combustible character.

Because of the relatively intense heat to 15 which the screen breaker is subjected, its action upon the fuel will be so nearly instantaneous that it will be substantially dry during operation. In other words, the substantially vertical disposition of the screen 20 presents an area capacity sufficiently in excess of the capacity necessary, to insure a substantially dry screen under actual operation. This is due to the fact that the fuel is permitted to spread over the surface of the 25 screen to a maximum thereby permitting the screen to function almost instantly in reducing the liquid particles to a dry gas. The screen also functions to cut the liquid particles of fuel thereby causing almost instant 30 gasification when the particles burst and this result is obtained by a screen of extremely fine mesh.

As a direct result of the normally dry condition of the screen, which is completely 35 dried immediately after the engine stops, the screen functions to collect, in the form of a film, the condensed gases that drain down the manifold after the parts are cool. I have found in practice that this film of condensation 40 efficiently impregnates the first inrush of air on restarting so as to give an effective explosion without waiting for the parts to heat up and I have actually started an absolutely cold engine, with this device, 45 on a low grade hydrocarbon without priming. I have proven this fact by not only performing this operation, but I have taken the screen out of the homogenizer immediately after stopping the engine and found 50 it to be absolutely dry. I have also taken the screen out after the parts cooled off and found the screen coated with a film of condensation.

It is believed that the novelty and utility 55 of my invention will be fully understood from the foregoing description, and while I have herein shown and described one specific form of my invention, I do not wish to be limited thereto except where such limitations 60 as the claims may import.

I claim:

1. In a homogenizer, a casing for passage of the fuel to be homogenized therethrough, a hollow heating shell disposed in said casing 65 in the path of the fuel to spread the fuel

against said casing, a screen diagonally disposed between said casing and shell to be heated by said shell and casing and break up the fuel particles carried by the mixture in the passage of the fuel through said screen, and means for supplying heat to the exterior of said casing and to the interior of said shell, substantially as described. 70

2. In a homogenizer, a casing for passage of the fuel to be heated therethrough, a hollow heating shell disposed in said casing in the path of the incoming fuel to deflect the fuel against the interior of said casing and said shell being slightly smaller than said casing, a fine screen in the path of the fuel between said shell and casing, and means for supplying heat to the exterior of said casing and to the interior of said shell to heat the casing and shell and said screen, substantially as described. 80

3. In a homogenizer, the combination with a casing and a shell within said casing and separated from the latter by a narrow space, a fine screen in said narrow space for passage of the fuel therefor and said screen being in close relation to said casing and shell to be heated to substantially the temperature of said casing and shell, means for supplying heat to said casing and to the interior of said shell, means for delivering fuel to be homogenized against one side area of said shell, and means for discharging the heated and mixed fuel from the opposite side of said casing with respect to the fuel entrance side, whereby all the entering fuel is spread against the hot interior of said casing and against the hot exterior of said shell and after heating and mixing is collected and delivered as hot carbureted air of homogeneous character. 100

4. In a homogenizer, a shell for passage therethrough of the fuel to be homogenized, means applying heat to said shell, an inner shell heated to substantially the same temperature as said passage shell and disposed inside of the latter and deflecting incoming fuel against said passage shell, said inner heated shell being extended along said passage shell sufficiently to present a heated surface to the fuel rebounding off from said passage shell, and a screen extending diagonally across the space between said shells for passage of the fuel through said screen during flow of the fuel from contact with said passage shell toward said inner shell, said screen being sufficiently close to said shells to be heated to substantially the same temperature as the latter, substantially as described. 110

5. As an article of manufacture of the class described, a truncated conical screen having an expansively acting spring secured to one margin thereof and a contractile spring secured to the other margin thereof, said screen having an opening between its 120

6. In a homogenizer, an open ended outer shell having inlet and outlet passages for exhaust gases, a bottom having a shoulder fitting against the edge of said lower open end of said shell and being provided with an internally threaded shoulder and also a fuel inlet opening, a top having a shoulder fitting against the edge of the upper open end of said shell and having an internally threaded shoulder and also a fuel outlet opening, a central open ended shell in threaded engagement with the threaded shoulders of said top and bottom portions to hold the latter in tight engagement with said outer shell and dividing said outer shell into a horizontal outer annular exhaust passage chamber and an inner vertical fuel passage chamber and the latter being in communication with said fuel inlet and outlet openings, and a fuel heating shell disposed in the path of the fuel flowing through said central shell and having communication with said outer shell for passage of a portion of the exhaust gases through said heating shell from said outer shell, substantially as described.
7. In a homogenizer, a fuel passage chamber, a deflector in said chamber for deflecting the fuel against the walls of said chamber, means for heating said chamber, and an expandible and contractible screen structure shaped to be sprung into position between and in resilient engagement with said chamber and deflector, substantially as described.
8. In a homogenizer, a fuel passage chamber, a deflector in said chamber for deflecting the fuel against the walls of said chamber, means for heating said chamber, and a resilient screen structure shaped to be sprung into position between and in resilient engagement with said chamber and said deflector, substantially as described.
9. In a homogenizer, an annular fuel passage chamber, means for heating said chamber, a heating chamber concentrically disposed in said passage chamber and having tubular connections extending across the space between said chambers and supporting said heating chamber by connection with said passage chamber and forming ingress and egress connections for supply and discharge of heat from said means to said heating chamber, and annular screen having openings shaped to fit about said tubular connections and support said screen in position between said chambers, said screen being split from said openings to one margin of said screen to permit said screen to be sprung into and out of position, substantially as described.
10. In a homogenizer, an annular fuel passage chamber, means for heating said
- chamber, a heating chamber concentrically disposed in said passage chamber in the path of flow of fuel therethrough, and an annular screen interposed between said chambers in the path of flow of the fuel therebetween, said screen having an expansively acting spring anchoring one of its margins to said passage chamber and being provided with a contractile spring anchoring the remaining margin of said screen to said heating chamber, substantially as described.
11. In a homogenizer, an annular fuel passage chamber having an outer heated wall, a heating shell disposed in said passage chamber in the path of flow of the fuel therethrough, and an annular screen interposed in the path of fuel flow and disposed in said passage, said screen having means for anchoring one margin thereof to said outer wall and having means for anchoring the remaining margin of said screen to said shell, substantially as described.
12. In a homogenizer, an open ended outer shell having an inlet and an outlet for passage of exhaust gases, a bottom having a shoulder fitting against the edge of the lower open end of said shell and being provided with an internally threaded shoulder and also with a fuel inlet opening, a top having a shoulder fitting against the edge of the upper open end of said shell and having an internally threaded shoulder and also a fuel outlet opening, a central open ended shell in threaded engagement with the threaded shoulder of said top and bottom portions to hold the latter in tight engagement with said outer shell and dividing said outer shell into a horizontal outer annular exhaust passage chamber and an inner vertical fuel passage chamber with the latter communicating with said fuel inlet and outlet openings, said central shell having radially inwardly extending inlet and outlet tubes terminating in an annular open ended shell, thin flash disks attached to the upper and lower ends of said inner shell to form an inner heating chamber in communication with said outer annular chamber for passage of the exhaust gases into and through said inner chamber, and an annular screen disposed diagonally across the annular space between said central and inner shells, substantially as described.
13. In a homogenizer, an open ended outer shell having an inlet and an outlet for passage of exhaust gases, a bottom having a shoulder fitting against the edge of the lower open end of said shell and being provided with an internally threaded shoulder and also with a fuel inlet opening of reduced diameter with respect to and concentrically disposed with respect to said shoulder, a top having a shoulder fitting against the edge of the upper open end of said outer

shell and having an internally threaded shoulder and also a fuel outlet opening, a central open ended shell in threaded engagement with the threaded shoulder of said top and bottom portions to hold the latter in tight engagement with said outer shell and dividing said outer shell into a horizontal outer annular exhaust passage chamber and an inner vertical fuel passage chamber with the latter communicating with said fuel inlet and outlet openings, said central shell having inwardly extending inlet and outlet tubes terminating in an inner annular open ended shell, thin flash disks attached to the upper and lower ends of said inner shell to form an inner heating chamber in communication with said outer annular chamber for passage of the exhaust gases into and

through said inner chamber, the lower portion of said inner shell having an external groove and the upper portion of said central shell having an upper internal groove, an inverted truncated split screen having a contractile annular spring on its lower smaller end fitting in said external groove and an upper annular expansive spring fitting in said internal groove to anchor said screen diagonally across the path of the fuel passing between said inner and central shells, and said screen having openings fitting externally about said tubes, substantially as described.

In testimony that I claim the foregoing as my own, I hereby affix my signature.

FRED WALLACE THURSTON.
